UNITED STATES PATENT OFFICE.

FREDRIC M. PARKER, OF WORCESTER, MASSACHUSETTS, ASSIGNOR TO
WILLIAM JAMES HOGG & SON, OF SAME PLACE.

DESIGN FOR CARPETING.

SPECIFICATION forming part of Design No. 29,210, dated August 9, 1898.

Application filed June 6, 1898. Serial No. 882,783. Term of patent 3½ years.

To all whom it may concern:

Be it known that I, FREDRIC M. PARKER, a citizen of the United States, residing at Worcester, in the county of Worcester and State of Massachusetts, have invented and produced a new and original Design for Carpets; and I do hereby declare that the drawing accompanying this specification gives and conveys to any one skilled in the art of carpet-weaving a clear understanding of the same that is sufficient to enable such persons to use my invention.

My invention relates to a design to be worked into or upon carpeting or similar fabrics.

The said drawing is a face view of a carpet embodying my new design. The drawing illustrates a body and a border.

The body A consists of a substantially uniform groundwork, upon which appear long curling leaf forms surrounding and supporting conventionalized floral figures.

The border B consists of a main part resembling the body A, an inner edge defined by a series of small ornamental figures, and an outer margin formed by a series of conventionalized floral figures resembling those of the body A.

What I claim, and desire to secure by Letters Patent, is—

1. In a design for carpeting, the body A, substantially as shown and described.
2. In a design for carpeting, the border B, substantially as shown and described.
3. The design for carpeting, consisting of the body A and the border B, substantially as shown and described.

FREDRIC M. PARKER.
